UNITED STATES PATENT OFFICE.

ALEXANDER M. CRAIG, OF ROME, NEW YORK, ASSIGNOR TO ROME SADDLERY HARDWARE MANUFACTURING COMPANY, OF ROME, NEW YORK, A CORPORATION.

FLEXIBLE METAL HAME-TUG.

No. 823,158.

Specification of Letters Patent.

Patented June 12, 1906.

Application filed December 6, 1904. Serial No. 235,776.

To all whom it may concern:

Be it known that I, ALEXANDER M. CRAIG, a subject of the King of Great Britain, now residing in the city of Rome, county of Oneida, 5 and State of New York, have invented an Improved Flexible Metal Hame-Tug, of which the following is a specification.

This invention relates to improvements in harness, and particularly to flexible metallic 10 hame-tugs; and it consists in the structure substantially as hereinafter described and claimed.

In the accompanying drawings, which form a part of this specification, Figure 1 15 shows in elevation a portion of a harness embodying my invention. Figs. 2 and 4 represent parts of a trace-carrier. Fig. 3 is a longitudinal section through the middle of the hame-tug and end of the trace.

20 In the drawings *g* represents the back-pad of a harness, *M* a trace, and *A* and *B* the trace-carrier, which form the subject of a divisional application, filed October 23, 1905, Serial No. 284,127, while the hame-tug consists, essentially, 25 of the metal links *1* and the clip *E*, by which it is attached to a hame.

The links of the hame-tug are in the main of the same structure as the links of an ordinary separable-link sprocket-chain. Each 30 of the links has a hinge portion or knuckle *h* at one end and a bar *i* at the other, which serve as the hinge-pintle for the adjacent link. On the face of each link in front of the bar *i* there is a groove *j*, and, preferably, on 35 the back a corresponding groove which permits the hinge-knuckle *h* to be slipped along the bar *i* of the adjacent link to the middle thereof in the well-known manner. Thus the length of the tug may be readily changed 40 by the insertion or removal of links. To adapt these links to the present invention, a cross-bar *c* is added for the attachment of the trace to the hame-tug. In the end of the

trace is secured a hook *f*, formed, as shown, 45 so that it may be easily applied to any of the

cross-bars *c* of said links in taking up or letting out a trace. The links are also preferably provided with means for the attachment thereto of a wear-leather *k*. This may be perfected by forming perforated lugs *d* 50 upon the cross-bars *c*, through which and the wear-leather may be passed rivets, as shown.

The last link of the hame-tug may be provided with an eye through which is passed 55 one end of the double loop *A*, which loop passes also through the loop *B*, and the trace passes easily through both ends of loop *B*; but this structure is not claimed herein, since it forms the subject-matter of the divisional 60 application referred to above.

The invention claimed is—

1. A metallic hame-tug consisting of a series of links, each having a cross-bar provided with means for attachment to a strip of wear- 65 leather.

2. A metallic hame-tug consisting of a series of separable metal links each having a cross-bar provided with a perforated lug for the insertion of the rivet by which to attach 70 the link to a strip of wear-leather.

3. The combination with a metallic hame-tug consisting of a series of links, each having a cross-bar provided with means for attachment to a strip of wear-leather, of a trace 75 having a bifurcated hook at its ends for engagement with the under side of said cross-bar.

4. In a flexible metallic hame-tug a link forming a removable section of said tug and 80 having at one end a knuckle and at the other a bar forming a hinge-pintle and intermediate of the ends a cross-bar provided with means for attaching the link to a strip of wear-leather.

ALEXANDER M. CRAIG.
